SIDING CLAMP

Ray E. Blomstrom, Pillager, Minn.

Application October 26, 1940, Serial No. 362,973

3 Claims. (Cl. 254—15)

This invention relates to a device for moving and holding boards or similar members in desired position. While the device might have various applications, it particularly is designed for use in arranging and holding siding, weather stripping or weatherboard, clapboards and the like. In placing such boards in position they are successively nailed to joists or studding and extend transversely thereof. It is necessary to bring the board to be nailed into proper position and the board to be placed and nailed is often warped or bent. It must be forcibly brought into engaging parallel or proper position to the boards already in place.

It is an object of this invention to provide a simple and efficient tool for engaging the board to be placed or nailed and moving the same into proper position and holding it in such position until it is secured in place.

It is a further object of the invention to provide a very simple and efficient tool which can be readily changed to be either a right hand or a left hand tool. This enables it to be used at either end of a section of boards, etc.

It is still another object of the invention to provide a simple and efficient tool for moving and holding boards, such as siding, into place including a lever handle and means on said handle for engaging with the siding for holding the tool in tightened position.

These and other objects and advantages of the invention will be fully set forth in the following description made in connection with the accompanying drawing in which like reference characters refer to similar parts throughout the several views and in which:

Fig. 1 is a view in front elevation of the tool showing the same applied to the boards to be operated upon;

Fig. 2 is a view as seen from the left of Fig. 1;

Fig. 3 is a perspective view of the tool, another position of the parts being shown in dotted lines;

Fig. 4 is a view similar to Fig. 3 showing the tool in reverse position to that shown in Fig. 3;

Fig. 5 is a partial view showing the holding pawl on the tool, said pawl being indicated in another position in dotted lines; and

Fig. 6 is a view as seen from the right of Fig. 5.

Referring to the drawing, a device or tool is shown comprising a lever member 10. Lever 10 is formed as an elongated bar and as a cylindrical handle portion 10a extending at right angles thereto at its end. The lever is thus a handle lever and the same has pivotally connected thereto in spaced relation adjacent the end opposite

that having portion 10a, members 11 and 12. Member 11 is connected to lever 10 by a rivet 13 having countersunk heads in both member 11 and lever 10. Member 11 extends transversely of lever 10 at right angles thereto and then is bent to extend in inclined position and is provided with a hooked end terminating in a flat rectangular portion 11a. Portion 11a is disposed in a vertical plane at one side of the plane occupied by lever 10. Member 12 is pivoted to lever 10 by a nutted bolt 14 which has a head countersunk in lever 10. Member 12 is provided with a plurality of holes 12a in any one of which bolt 14 may be disposed. It will be seen that member 12 is at the side of lever 10 opposite that on which member 11 is disposed and member 12 also extends transversely of lever 10 substantially at right angles thereto in a direction opposite to that in which member 11 extends. Member 12 is also bent to extend in an inclined direction some distance from lever 10 and is provided with a curved hooked end 12b. The terminal part of portion 12b is disposed in a plane at one side of the plane occupied by lever 10. Lever 10 has pivoted thereto adjacent handle 10a 20 a pointed pawl 15 which curves away from lever 10 in a direction opposite to that in which handle 10a extends. Pawl 15 is connected to lever 10 by a rivet 16 countersunk into pawl 15. Stop lugs 10b and 10c are formed on lever 10 against which the sides of pawl 15 engage to hold said pawl in operative position with the tool in right hand or left hand position respectively.

In operation, the boards 20 will be nailed to the supporting studding or joists. Assuming the lower boards 20 to be in position the board 20a at the top will be placed in engaging position with the top board 20 already secured. It may be that the top board 20a will not fit into proper position. The tool is then applied with the hook portion 12a engaging under the edge of the top board 20 already secured. The portion 11a is engaged along the top edge of the board 20a. It is usually the case that the boards are provided with interengaging tongues and grooves. It will be seen that the portion 11a can conveniently be placed along the ledge at one side of the tongue 20b of the board to be secured. With members 11 and 12 so placed lever 10 is now swung downward as shown in Fig. 1 and this action pulls downward on member 11 and upward on member 12. As the top board 20 is already fixed this action pulls the board 20a to be secured firmly and properly in place in engagement with the top board 20. When lever 10 is moved downward to bring board 20a into proper position

it can be held in this position by engaging the pawl 15 with the board 20 already in place. The operator can now nail the top board 20a in position. The operation is repeated with each successive board which it is necessary to move to proper nailing position. When the operator gets to the right hand end of the boards as shown in Fig. 1 and pulls the board 20a into place with the tool the lever 10 and parts 11 and 12 will interfere with the nailing. The tool as shown in Fig. 1 could be called a right hand tool with lever 10 extending to the right. The tool can be readily changed to a left hand tool by swinging members 11 and 12 about their pivots so that they occupy a reverse position relative to lever 10. Lever 10 then extends to the left as shown in Fig. 4. The tool in this position can be applied to the right hand ends of the boards and the end portions of the boards will then be at the right hand end of the tool and beyond the same. The operator can then readily drive the nails without any interference from the tool. It will be noted that pawl 15 can also be swung into opposite positions so that it will be in proper engaging position whether the tool is in the position as a right hand tool or a left hand tool. It will be seen that the members 11 and 12 can swing past each other when they are rotated through substantially 180 degrees to change the tool from a right hand to a left hand tool or vice versa.

From the above description it will be seen that I have provided an extremely simple and highly efficient tool for use in placing and nailing boards such as described. The operation of the tool is quite easy and rapid and the placing of the boards is greatly speeded up and facilitated. The device has been amply demonstrated in actual practice, found to be very successful and efficient and is being commercially made.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A device for holding boards for nailing having in combination, an elongated lever having a handle at one end, members pivoted to said lever in spaced relation longitudinally thereof adjacent its other end and extending at opposite sides transversely of said lever, said members extending to vertical planes at one side of said lever and having hook portions at their free ends with a part disposed in said planes respectively constructed and arranged to engage respectively the edges of boards to move one of them into de-

sired position, said members and lever being swingable past each other about their pivoted connections so that said device may be arranged in operative position with said handle extending either to the right or to the left and means on said lever adjacent said handle to hold said lever with the device in tightened position, said means being movable to either side of said lever for use with the lever extending either to the right or to the left.

2. A device for holding boards for nailing having in combination, an elongated lever having a handle at one end, members pivoted to said lever in spaced relation longitudinally thereof adjacent its other end and extending at opposite sides transversely of said lever, said members extending to vertical planes at one side of said lever and having hook portions at their free ends with parts disposed in said planes respectively constructed and arranged to engage respectively the edges of boards to move one of them into desired position, said members and lever being swingable past each other about their pivoted connections so that said device may be arranged in operative position with said handle extending either to the right or to the left, a pawl pivoted to said lever adjacent said handle for holding said lever with the device in tightened position, said pawl being swingable to either side of said lever so as to be used with said lever extending to the right or to the left and stop means on said lever engaged by said pawl when in holding position.

3. A device for holding boards for nailing having in combination, an elongated lever, a member pivoted at one end of said lever and arranged to extend transversely thereof, said member being bent to extend toward the plane of said lever and having a hook portion at its end adapted to engage over the edge of a board, a second member pivoted to said lever adjacent said mentioned member at the opposite side thereof and bent to extend away from the plane of said lever and having a hook portion at its end disposed substantially in the same plane as said first mentioned hook portion, said lever having a handle projecting at right angles thereto at its other end and extending in a direction opposite to that in which said members are bent, a pawl adjacent said handle pivoted substantially centrally transversely of said lever, adapted to be moved to position so as to be directed at opposite sides of said lever and stops on said lever holding said pawl in said positions, said members being capable of being rotated about their pivots through 180 degrees to swing past each other and be reversed in position so that said lever will project in opposite operative positions.

RAY E. BLOMSTROM.
